UNITED STATES PATENT OFFICE.

HORACE C. WILCOX, OF WEST MERIDEN, CONNECTICUT, ASSIGNOR TO THE MERIDEN BRITANNIA COMPANY, OF SAME PLACE.

DESIGN FOR CAKE OR FRUIT BASKETS.

Specification forming part of Design No. 7,111, dated January 13, 1874; application filed December 27, 1873.
[Term of Patent 3½ years.]

To all whom it may concern:

Be it known that I, HORACE C. WILCOX, of West Meriden, in the county of New Haven and State of Connecticut, have invented a new Design for Basket; and I do hereby declare the following, when taken in connection with the accompanying drawing and the letters of reference marked thereon, to be a full, clear, and exact description of the same, and which said drawing constitutes part of this specification, and represents a perspective view.

This invention relates to a design for the article of table service commonly called cake or fruit basket, the design consisting in the configuration of three parts, which may be used together or separately—viz., the legs or support, the basket or plate, and the handle.

The legs, starting from the foot or bearing point *a*, run straight, but obliquely, to near a common center, *b*. A little below the upper end of this part a branch, *c*, extends from this part obliquely outward and upward to the basket at *d*. At the intersection of the two parts of the leg an ornament, *f*, is introduced, having the appearance of a brace. The basket,

resting upon the legs, has a flaring scalloped edge, as shown. For the bail, a branch, *h*, extends up from each side the basket, inclined inwardly, and near the upper end each branch intersects a bar, *n*; these bars *n*, running in an upward incline, meet at the center. An ornament, *r*, is introduced at the intersection of the bars *h* and *n*.

These legs may be used for other baskets and with different bails, and vice versa. I therefore do not confine myself to the combination of the three parts described, but together or separately.

I claim as my invention—

The design for basket, as shown in the accompanying illustration and herein described, consisting of the legs in two oblique parts, the basket with a flaring scalloped edge, and the bail formed of inclined parts *h* *n*, the said legs, basket, and bail used together or separately.

HORACE C. WILCOX.
